WEIGHING SYSTEM

Charles V. Hallenbeck, Denver, Colo.

Application August 9, 1932, Serial No. 628,016

12 Claims. (Cl. 249—25)

This invention relates to a weighing system and to buckets of the type used in plants for producing a mixture of oil or asphalt, and sand or gravel for use in road building or other construction work. It is customary to employ a bucket for the oil or asphalt, and in connection therewith a weighing mechanism so that each batch of liquid may be weighed before it is discharged into the pug mill or other receptacle where the mixture is made.

Owing to the fact that the weight of the bucket itself is often varied by reason of the adherence of sand or gravel to its exterior oil or asphalt coated surfaces, it has heretofore been necessary to weigh each batch of oil or asphalt which obviously is a laborious and time-taking task.

It is an object of the present invention to provide means for obviating repeated weighing of the bucket and its contents, by overflows and adjustments which permit of automatically determining the contents of the bucket each time it is loaded according to a predetermined measure established by weighing the bucket and its load at the beginning of the operation.

A controlling factor in this automatic measuring process, is an overflow for the discharge of surplus liquid from the bucket, and it is another object of the invention to collect this overflow and return it to the source of supply in a closed circuit.

Further objects are to be found in details of construction and in novel and advantageous arrangements of parts as will be fully disclosed in the following description with reference to the accompanying drawings.

In the drawings, in the various views of which like characters of reference designate corresponding parts,

Figure 1 represents a side elevation of the measuring bucket and the therewith associated weighing and operating mechanisms.

Figure 2 is a sectional side elevation of the construction shown in Figure 1, and

Figure 3 is a fragmentary and partially sectional side view of the bucket, looking in the direction of the arrows on the line 3—3 of Figure 2.

The bucket 5, as shown in the drawings, is preferably of V-shaped section and it has at its ends downwardly projecting apertured lugs 6, for its pivotal suspension in a bail composed of a tubular horizontal member 7 above the bucket and side bars 8 which are pivotally connected with the lugs by studs 9. The studs are at the ends of arms 10, pivotally connected with parts 12 of the supporting structure. It will thus be seen that

the suspension bail may move vertically, while the bucket may swing in the bail about its pivots.

The pivotal movement of the bucket is variably limited by set-screws 13 adjustable on the side-bars 8 of the suspension-bail and engaging with stops 14 at the ends of bucket. Counter weights 15 on arms 16 projecting slantingly downwardly from the ends of the bucket maintain its stops in engagement with the ends of the set-screws and provide for the automatic return of the bucket to its normal position after each dumping movement thereof. This return movement of the bucket may be regulated by adjustment of the weights on their arms.

The bucket is by medium of its bail suspended from a weighing mechanism, which, as shown in the drawings, comprises a scale-beam 17 fulcrumed as at 18, beneath an overhead stationary rafter 19 of the supporting structure of the plant of which the measuring bucket is a part. The beam 17 is, as usual, equipped with a suspended weight carrier 20 and with a sliding poise 21. Suspended from the beam is a yoke 22 having two cross-pieces for engagement with knife-edges 23 and 24 at the ends of two levers 25 and 26, which are pivotally suspended from hangers 27 on the overhead rafter by links 28. Clevises 29 suspend the bail of the bucket from the levers 25 and 26 at one side of their respective fulcrums.

The top of the bucket is partially closed by a cover plate 30, which, adjacent the forward side of the bucket, has an opening 31 for the discharge of the contents of the bucket when the latter is swung about its pivots in a forward direction.

To facilitate the manual movement of the bucket, it is provided with a forwardly extending handle 32.

The size of the discharge-opening may be varied by means of a sliding gate 33 on the cover, which is held in its adjusted positions by a plurality of bolts 34. The contents of the bucket are dumped into a pug mill or other receptacle forming part of the plant and indicated at 35, and bumpers 36 at the forward side of the bucket, limit its downward movement by engagement 45 with the pug mill, as shown in broken lines in Figure 2.

The bumpers are fastened at the ends of a channel bar 37 secured at the forward side of the bucket.

At the rearward side of the bucket are a number of elongated overflow-openings 38 at different elevations, as clearly shown in Figure 3 of the drawings. Each of these openings may be separately closed by a cover-plate 39 clamped in

place by means of wing-nuts 40 on bolts 41. Bow-springs 42 straddling the openings and engaged by the nuts 40 hold the plates in fluid-tight engagement with the inner surface of the side plate 5 of the buckets, in which the overflow-openings are formed.

Beneath the bucket at its overflow side is a receiver 43 for the overflowing liquid. The oil or asphalt is supplied to the bucket from a conveniently located source of supply, and a conduit shown at 45a, returns the contents of the receiver to the source in a substantially closed circuit. It will be understood without detailed illustration that a pump or other similar device may be employed for this purpose. The source has been shown in broken lines at 44 in Figure 2 and a pump has been indicated at 45.

A spout 47 conducts the material from the source to the bucket, and a gate valve 48, provided with a handle 49, controls the flow through the spout 47. The handle 49 preferably extends over the bucket so that it may be reached by the operator who tilts the bucket by means of the handle 32.

25 In the operation of the measuring bucket, the empty bucket is weighed first of all, after which the weighing scale is set to balance the bucket and the quantity of oil or asphalt constituting the batch to be delivered to the pug mill in each operation.

The liquid is then poured into the bucket from the source of supply until the weighing scale is in balance, after which the overflow opening or openings nearest the level of the liquid are opened by 30 removal of the respective cover-plates.

The bucket is then tilted rearwardly, as indicated in broken lines in Figure 2, until the level of the liquid is in alinement with the lower edges of the uncovered openings and the set screws 13 are adjusted to engage the stops 14 in this position of the bucket. It will be apparent that after these adjustments have been made, the bucket may be repeatedly filled until the liquid flows out of the uncovered openings and that each time 45 the weight of the contents of the bucket will be equal to that originally determined by means of the weighing mechanism.

The overflowing liquid drops into the receiver 43 and is returned without loss, the bucket having at the bottom of its rearward side, a trough 46 to catch drippings and convey them to the receiver. The bucket is emptied by tilting it forwardly by means of the handle 32, as hereinbefore explained, and it is automatically returned to its original 55 position in which the stops engage the ends of the set screws, by the counterweights 15.

60 The opening 31 at the top of the bucket controlled by the adjustable gate, permits the discharge of the liquid in a thin stream, it being desirable that the length of the bucket be but slightly less than the width of the pug mill or other receptacle into which the liquid is dumped.

What I claim and desire to secure by Letters Patent is:

65 1. In apparatus of the character described, a suspension bail, a bucket pivoted in the bail and having overflow openings at different elevations, removable closures for the openings, and means for limiting pivotal movement of the bucket, to establish a liquid-level in alinement with one of the overflow-openings, including a set-screw on the bail, and a stop on the bucket, engaged by the set-screw.

70 2. In apparatus of the character described, a pivoted bucket having an overflow-opening on one

side of the pivot for establishing a predetermined liquid-level in a position of rest of the bucket, and having a discharge-opening on the other side for the delivery of its contents in a tilted position, means comprising a stop establishing said position of rest of the bucket, and an adjustable counterweight opposing movement of the bucket out of its position of rest. 5

3. In apparatus of the character described, a pivoted bucket having an overflow-opening establishing a predetermined liquid-level in a position of rest of the bucket, and having a discharge opening for the delivery of its entire contents in a tilted position, the discharge-opening extending substantially along an entire side of the bucket, and flow-restricting means limiting the width of the discharge-opening. 10

4. In apparatus of the character described, a pivoted bucket having an overflow-opening establishing a predetermined liquid-level in a position of rest of the bucket, and having a discharge-opening for the delivery of its entire contents in a tilted position, the discharge-opening extending substantially along an entire side of the bucket, and an adjustable gate limiting the width of the discharge-opening. 15

5. In apparatus of the character described, a pivoted bucket having one side provided with an overflow-opening establishing a predetermined liquid-level, and having the other side provided with an opening for the discharge of its contents while in a tilted position, a source of liquid-supply, a receiver for overflowing liquid, and means for returning liquid from the receiver to the source. 30

6. In apparatus of the character described, a pivoted bucket having an overflow-opening on one side of the pivot for establishing a liquid level in a predetermined position of rest of the bucket, stop-means determining said position of rest, a downwardly slanting arm on the same side of the pivot as the overflow opening, and a weight on the arm effecting movement of the bucket to its said position of rest and opposing its movement therefrom, the bucket being adapted to discharge its 45 contents in a tilted position. 45

7. In apparatus of the character described, a pivoted bucket having an overflow opening on one side of the pivot and normally at a given distance above its bottom for removal of the contents of the bucket in excess of a measured quantity, and means for adjusting the bucket about its pivot, whereby to dispose the opening at a different elevation above the bottom to vary the measured quantity. 50

8. In apparatus of the character described, having a weighing element, a pivoted bucket suspended from said element and having an overflow-opening normally at a given distance above its bottom for removal of the contents of the bucket in excess of a measured quantity and having a discharge-opening on the other side of the pivot to effect the delivery of the measured quantity from the bucket, and means for adjusting the bucket about its pivot, whereby to dispose the 65 overflow-opening at different elevations above the bottom to vary the measured quantity. 55

9. In an apparatus of the class described, a support, a bucket pivotally connected thereto, for rocking movement about the pivot, an adjustable stop for limiting the rocking in one direction while permitting it to be rocked freely in the other direction to effect a discharge of the contents thereof, the side of the bucket corresponding to the limited rocking movement having a plurality of 70 75

overflow openings located at different levels and provided with removable closures for effecting a major adjustment of the capacity of the bucket, and means comprising the adjustable stop for effecting a simultaneous vertical adjustment of all of the overflow openings to effect a more delicate adjustment of the capacity of the bucket.

- 5 10. In an apparatus of the class described, in combination, a support, a bucket pivotally connected thereto, the bucket being freely rockable in one direction to effect a discharge of its contents, a stop for limiting the rocking in the other direction, the side of the bucket corresponding to the limited rocking movement having an overflow opening, means for adjusting the vertical position 15 of the opening with respect to the pivot, to vary the capacity of the bucket when the stop is effective, and means for urging the bucket into stop-engaging position.
- 15 20. In an apparatus of the class described, in combination, a support, a bucket pivotally connected thereto, the bucket being freely rockable in one direction to effect a discharge of its contents, a stop for limiting the rocking in the other

direction, the side of the bucket corresponding to the limited rocking movement having an overflow opening, means for adjusting the vertical position of the opening with respect to the pivot, to vary the capacity of the bucket when the stop is effective, and means for urging the bucket into stop-engaging position, said means consisting of a weight located on the same side of the pivot as the overflow opening.

- 5 10. In an apparatus of the class described, in combination, a supporting-element, a bucket pivotally connected thereto, one side of the bucket having an overflow opening and the opposite side a discharge opening, adjustable stop means for limiting the pivotal movement in the direction of 15 the side having the overflow opening while permitting the bucket to rock sufficiently in the other direction to effect a discharge of its contents, the bucket being overbalanced for the purpose of normally making the stop effective, and means comprising the adjustable stop for adjusting the vertical position of the overflow opening to vary the capacity of the bucket.

CHARLES V. HALLENBECK.
